UNITED STATES PATENT OFFICE.

HENRY L. CROLL, OF NEW YORK, N. Y.

DESIGN FOR A BOX-COVER.

SPECIFICATION forming part of Design No. 36,317, dated May 12, 1903.

Application filed March 20, 1903. Serial No. 148,798. Term of patent 3½ years.

To all whom it may concern:

Be it known that I, HENRY L. CROLL, a citizen of the United States, and a resident of the city of New York, borough of Manhattan, in the county and State of New York, have invented and produced a new, original, and ornamental Design for a Box-Cover, of which the following is a specification, reference being had to the accompanying drawings, forming part thereof, and in which—

Figure 1 is a plan view of the box-cover, and Fig. 2 a cross-section thereof.

The design is produced on the top of the cover and consists in a major wreath *a*, inclosing two minor wreaths *b* and *c*, and said

minor wreaths respectively inclosing portraits *d* and *e*.

Having described my invention, what I claim as new, and desire to secure by Letters Patent, is—

The ornamental design for a box-cover, substantially as herein shown and described.

In testimony whereof I have signed my name to this specification in the presence of two subscribing witnesses.

HENRY L. CROLL.
